BRYANT H. BLOOD, OF HARTFORD, CONNECTICUT, ASSIGNOR TO PRATT & WHITNEY COMPANY, OF NEW YORK, N. Y., A CORPORATION OF NEW JERSEY.

METHOD OF BURNISHING GEARS.

Application filed November 6, 1922. Serial No. 599,315.

To all whom it may concern:

Be it known that I, BRYANT H. BLOOD, a citizen of the United States, residing at Hartford, in the county of Hartford and 5 State of Connecticut, have invented certain new and useful Improvements in Methods of Burnishing Gears, of which the following is a specification.

This invention relates to an improved 10 form of gear burnishing device and to an improved method of burnishing gears.

An object of the present invention is to provide a gear burnishing machine or device adapted to facilitate and expedite the 15 mounting of the gear to be burnished and to enable a gear to be quickly burnished, preferably by a plurality of burnishers.

Another object of the invention is to provide a burnisher adapted to control the 20 burnishing action so that preferably points of the teeth on the gear being burnished and parts adjacent thereto will have more burnishing action applied to them than the remaining parts of the gear teeth.

25 Another object of the invention is to provide a burnishing machine or device mounting a plurality of burnishers in the form of gears, these burnishers having teeth of slightly different character in order to vary 30 their burnishing action upon the gear and adapted to control the burnishing action upon different parts of the gear being acted upon.

In practice, it heretofore has been the 35 custom to burnish gears by running them while in mesh with other gears of corresponding pitch until the surfaces of the gear being burnished are sufficiently uniformly smoothed for proper action. I have 40 found, however, that it is desirable to more strongly burnish the points of the teeth than the parts of the teeth adjacent and below the pitch circle. I am enabled to accomplish this object and to definitely control the 45 burnishing action by slightly varying the characters of tooth outlines on the burnishers.

In the succeeding paragraphs reference 50 will be made to the base circle, the pitch circle, addendum circle and the "normal pitch" of the gears. The base circle, pitch circle and addendum circle, are such well known terms in the art that a definition of them will be unnecessary. The term "nor-

mal pitch" is not so well or generally known 55 so that a definition of this term is necessary. This term refers to the base circle and indicates the pitch on that circle, that is, the linear distance between adjacent corresponding involutes as measured on arcs of this 60 base circle. Mathematically speaking, the "normal pitch" corresponds to the circular pitch of the gear multiplied by the cosine of the pressure angle. In other terms, it equal the circumference of the base circle 65 divided by the number of teeth in the gear.

It is therefore a principal object of the present invention to so form the tooth curves of the burnishers that they will concentrate their burnishing action upon the points of 70 the gear teeth and parts adjacent thereto. I accomplish this object by varying slightly the normal pitch of the involutes on the burnishers as compared with the normal pitch of the involutes on the gear. 75

Some of the advantages of my improved method of burnishing may be obtained by burnishing the tooth curves adjacent the base of the involutes instead of at and adjacent their outer points. 80

In order to concentrate the burnishing action adjacent the lower flank portions, I use a burnisher having teeth whose normal pitch is slightly increased instead of decreased as compared with the gear being 85 burnished. This gives a form of tooth of apparently slightly less pressure angle and the points on the teeth of the burnisher are therefore forced into strong contact with the flanks of the gear being burnished. In this 90 way, they contact with and concentrate their burnishing action upon these lower portions of the gear teeth.

In the drawings, forms of burnishers are disclosed which in their action concentrate 95 the burnishing of the tooth curves upon their points, their inner flank portions, and uniformly upon the involute contour, this being the preferred form of the invention. These burnishers may be used singly or in 100 groups as desired. It is to be understood, however, that certain conditions may arise wherein it will be more desirable that the teeth of the gears being burnished be more strongly burnished adjacent their roots 105 rather than at their points and I control this burnishing action by selecting burnishers having teeth of slightly modified

normal pitch. To concentrate the burnishing action on the points of the teeth the normal pitch of the burnisher is slightly lessened and to more strongly burnish the flanks or portions within the pitch circle, the normal pitch of the burnisher is slightly increased.

In either case, I prefer to run the gears being burnished in contact with a plurality of burnishers, one or more of which may be of modified normal pitch.

If a plurality of burnishers are used simultaneously, a method to be preferred, the base circles of the burnishers may be slightly varied between themselves. In each case the normal pitches of the tooth curves of the burnishers vary but slightly from the normal pitch of the gear being burnished.

The variation in the normal pitch of the tooth curves on the burnishers does not affect the other characteristics of the teeth on the burnisher. The number of teeth on the burnishers therefore may be selected for convenience and these may be used for burnishing gears having any number of teeth of the same nominal size.

With these and other objects in view, my invention consists in the features of construction and operation set forth in the following specification and illustrated in the accompanying drawing.

In the drawing annexed hereto and forming a part of this specification, I have shown my invention in the form of a device adapted to be mounted on a milling machine, but it will be understood that the invention can be otherwise embodied and that the drawing is not to be construed as defining or limiting the scope of the invention, the claims appended to this specification being relied upon for that purpose.

In the drawing:

Figure 1 is a front elevation of a device for burnishing gears made in accordance with the present invention.

Fig. 2 is a side elevation of the same.

Fig. 3 is a diagrammatic view showing the teeth of a gear and burnisher in intermeshing relation.

Fig. 4 is a view similar to Fig. 3, and

Fig. 5 is an enlarged view of a gear being burnished by three burnishers having different normal pitches.

In the above mentioned drawing, I have shown but one embodiment of the invention which is now deemed preferable but it is to be understood that changes and modifications may be made within the scope of the appended claims without departing from the spirit of the invention.

Briefly, my invention preferably comprises a device which for convenience may be mounted upon a milling machine of conventional or ordinary form and consists generally of; first, a base adapted to be directly fastened to the table of the milling machine;

second, a pair of burnishers in the form of gears rotatably mounted upon parallel axes in the said base; third, another burnisher of similar form which for convenience may be applied to the cutter spindle of the milling machine; and fourth, means to rotate one of the burnishers while the gear being burnished is in position to intermesh with all three burnishers.

Referring more in detail to the figures of the drawing, I show a milling machine 10 of conventional form having a vertically adjustable knee 11 on which is slidably mounted a saddle 12 which may be moved in a direction parallel to the axis of the cutter spindle 13 of the milling machine. On this saddle 12, or intermediate slide, is the usual reciprocatory table 14 which may be movable in a direction normal to that of the saddle or intermediate slide 12.

The milling machine 10 is provided with a cone pulley 15 or other driving means for the spindle 13, and also with an overhanging arm 16 of usual construction to aid in supporting an arbor 17 mounted on and rotated by the spindle 13.

A base 20 shown most clearly in Fig. 1 is fastened to the upper surface of the milling machine table 14 in any convenient way. Extending through this base member 20 are parallel spindles 21 preferably held fixedly therein by any convenient means. Rotatably mounted upon these parallel spindles 21 are burnishers 22 and 23 preferably of approximately equal size and numbers of teeth. These, as is usual in burnishing devices are hardened and are also preferably ground so that the tooth outlines thereon, which are usually of involute form, are correct to a high degree of precision.

Mounted on the arbor 17 of the milling machine 10 is a third burnisher 24 which may be directly fastened thereto so that it will rotate with the spindle and will be rotated by any convenient power means as by the pulley 15. By varying the elevation of the adjustable knee 11 and therefore the device mounted on the milling machine table 14, any sized gear may be mounted between the three burnishers, and, when the burnisher on the milling machine spindle is rotated, it will rotate the gear A being burnished and the two lower burnishers 22 and 23. By forcing the adjustable knee 11 vertically upward any desired pressure may be exerted by the burnishers 22, 23 and 24 upon the tooth curves of the gear A. I preferably form the burnishers 22, 23 and 24 of wider face than the gear A being burnished so that, if desired, the gear may be moved axially forward or backward to insure even wear on the burnishers and more uniform burnishing action on the gear.

In order to accomplish an improved burnishing action which will render the gear more quiet in operation than any other

method, I prefer to concentrate the burnishing action upon the points of the teeth, that is, upon the tooth curves of the gear being burnished outside of the pitch circle. 5 I accomplish this by varying the tooth curves on the burnishers with relation to the gears being burnished in such a way that they may have, or at least one of them may have, a normal pitch slightly less than the normal pitch of the gears being burnished. 10 Preferably as there are three burnishers simultaneously acting on the gear, I make one of these burnishers to correspond exactly with the normal pitch of the gear and the other two burnishers of different normal pitch, one of which may be slightly less than the normal pitch of the gear and the other slightly more, as shown in Fig. 5. If desired, however, all three of the burnishers 15 may be made of equal normal pitch slightly less than the normal pitch of the gear being burnished.

Referring to the diagrams in Figs. 3 and 4, a few of the teeth of the gear A being burnished in action with the teeth of a burnisher are described. In Fig. 3, the normal pitch of the burnisher 24 is identical with that of the gear A as indicated by the identical lengths of the lines *a* and *b*. In other words, the teeth of this burnisher are of the form of gear teeth adapted to intermesh with the gear in the usual manner. This figure shows the form of teeth on burnishers as they have usually been formed heretofore. In Fig. 4, the toothed curves of the burnisher 22 have been slightly modified so that they are involutes of a base circle slightly less than the involutes of the burnisher shown in Fig. 3; this is indicated by the line *c* being slightly less than the line *b*. 20

In these Figures 3 and 4 the dimensions indicated by the lines *a*, *b* and *c* are the normal distances between parallel planes in contact with corresponding sides of adjacent tooth curves. These dimensions also correspond exactly with the normal pitches respectively of the gear and burnishers. This dimension, that is, the normal pitch of the gear and burnisher, is preferably measured substantially in the manner indicated as by obtaining the distance between parallel planes provided on members of a measuring instrument when these are held in contact with adjacent teeth of a gear.

55 The teeth therefore of the burnisher in Fig. 4 in their intermeshing relation with the gear A being burnished will have their contact concentrated upon the points of the teeth, the greatest pressure being exerted at the extreme points and this pressure being gradually diminished until the pitch circle is reached. The flanks of the teeth or portions within the pitch circle are not acted upon at all by this burnisher having a shortened normal pitch. On the other hand,

the burnisher shown in Fig. 3, which has a normal pitch exactly corresponding to the teeth of the gear A being burnished, will have a burnishing action uniformly distributed over the entire involute surface of the 70 gear tooth.

In Fig. 5 three burnishers disposed in the same way as burnishers 22, 23 and 24 are shown, each having a slightly different normal pitch. In this figure "b" indicates 75 the normal pitch of the gear being burnished. The burnishers 22, 23 and 24 have, as indicated, normal pitches "*a*", "*b*" and "*c*" respectively less than, equal to, and greater than the normal pitch of the gear. 80

It will be seen from the above that I have provided a device for burnishing gears which will enable a gear to be quickly mounted in position to be burnished and which may be simultaneously acted upon by a plurality of burnishers preferably three being used as shown in the drawing. By making use of three burnishers 22, 23 and 24 so that they may engage the gear being burnished upon three approximately equally spaced 90 points, I am enabled to dispense with mounting the gear being burnished on centers or upon an arbor. To mount the gear such as shown at A, it is only necessary to place it in position to rest upon the burnishers 22 and 23 and then elevate the knee 11 until the gear A contacts with the rotating burnisher 24. The burnishers 22 and 23 may then be forced vertically upward until the gear A is forced into contact with all three burnishers. 100

What I claim is:

1. The process of burnishing gears comprising running said gear while in mesh with a burnisher, said gear and burnisher 105 being of slightly different normal pitch.

2. The process of burnishing gears comprising running a gear while in mesh with a burnisher, the normal pitch of the burnisher being slightly less than that of the 110 gear being burnished.

3. The process of burnishing gears comprising running a gear while in mesh with a plurality of burnishers, one of said burnishers having a normal pitch slightly different from that of the gear being burnished. 115

4. The process of burnishing gears comprising running said gears while in mesh with a plurality of burnishers, one of said burnishers having a normal pitch corresponding exactly with the gear being burnished, and another burnisher having a normal pitch slightly less than that of the gear. 120

5. The process of burnishing gears comprising running said gear while in mesh with three burnishers, one of said burnishers having a normal pitch corresponding exactly to the normal pitch of the gear being burnished, the other burnishers hav- 125 130

ing different normal pitches, the normal pitches of the latter burnishers being slightly less than the normal pitch of the gear.

6. The process of burnishing gears comprising running a gear while forced into contact with a plurality of approximately equally spaced burnishers whereby said gear may be retained in position by its engagement with said burnishers.

10. 7. The process of burnishing gears comprising running a gear while forced into contact with a plurality of burnishers mounted so as to be movable toward or from each other and adapted when in position to

retain the gear being burnished between them.

8. The process of burnishing gears comprising running a gear while forced into contact with three approximately equally spaced burnishers, two of said burnishers being movable toward or from the other, and rotating all of said burnishers and gear from one of said burnishers while said burnishers and gear are in mesh with each other.

In testimony whereof, I hereto affix my signature.

BRYANT H. BLOOD.
